(54) **WATER WHEEL, HORIZONTAL**

(76) Inventors: **John Mickolls; Solomon P. Wheeler**

John Nichols & Solomon P. Wheeler. Testimony.

Letter Patent

The Petitioners referred to in these Letter Patent and making part of the same containing a description in the words of the said John Nichols and Solomon P. Wheeler, themselves of their improvement in the horizontal current Water Wheel and inclined Race Wheel.

We it known that we John Nichols and Solomon P. Wheeler both of Bolivar Madison County State of Tennessee have made improvements in the Horizontal current Water Wheel and inclined race Wheel which are described as follows. The first wheel which we shall describe consists of the spiral screw shaft, the arms and swinging floats or buckets etc. the guard ring & top of the wheel for raising and lowering the guard ring, the horizontal cog wheel, the four bay and trough and sliding gauge. The second wheel which we shall describe consists of the shaft, the arms, swinging buckets & the inclined race or spout for conducting the water. ~~The first is current water wheel~~
The spiral screw shaft. This is made of metal or wood of any convenient size. A screw right or left of any pitch, is cut upon it from within a small distance of the bottom to any required height & it turns in bushes or guides or like other shafts for water wheels. The arms with the swinging float or bucket. Eight arms are made on both sides to a metal ring which having a projection in it to work in the arm on the shaft and notches or steps made on the upper side to receive the projections or steps of the guard ring to be hereafter described. Upon the extremities of the arms are suspended the swinging floats by means of hinges. The floats are made fan shaped being narrowest near the shaft. A circular frame of wood or metal embraces all the arms on the upper side all around and forms a brace to the arms. upon this circular frame and near each arm is placed a small frame having a stalk with a circular head having

tho' the frame for supporting the swinging buckets whilst the frame of arms and buckets are lowered on the lower shaft. The guard ring & stop. A metallic ring embracing the shaft having projections extending on the lower side to be suspended by ropes or chains from a windlass placed on the horizontal cog wheel to be hereafter described. This guard ring is for keeping the frame of arms and buckets at any required height on the shaft by means of the teeth on the ring catching in the notches of the hub which support the arms. It also catches in grooves cut in the shaft to prevent it turning. A Horizontal cog wheel. which communicates motion to the mill is placed near the top of the shaft. Upon this wheel is put a windlass or capstan having two ropes or chains on it passing over pulleys placed near the shaft and attached to the guard ring by which it is raised or lowered on the shaft. The sliding gauge. In the frame of the tubbag is fixed the sliding gauge. This gauge consists of an upright shaft or stock with a spring behind it and working in a dovetailed groove. An arm projects from the upright stock or shaft at right angles and passes over the counter wheel to keep the swinging buckets horizontal. When it is required to let down the buckets the gauge is let down to touch the top of the crank handle which turns the circular head and let down the buckets. The fire bay and trough. Upon this horizontal water wheel is a swinging gate or water disc or turning on two pivots, fixed in the front of the fire bay. It is kept at any required angle by means of a stop or bar of iron having a slot or opening in it attached at one end to the gate and the other extending to the wall or frame of the fire bay where a screw passing through the slot fixes the gate at any angle and lets the water out of the wheel in any required angle. The wheel turns in a circular trough of a size adapted to the size of the wheel and the water is made to pass off in a proper stream.

Operation. When it is required to lower the frame of float or buckets the swinging floats are turned up and kept in a horizontal position by cranks on the circular frame. The frame of arms and floats

es than turned by hand on the screw-shaft and turned to any required height. The guard-ring is then let down by the wind-laps and the teeth in the ring catch into the notches of the ring or hub of the frame of arms and buckets. The swinging buckets are then let down by the gauge and the horizontal wheel set in motion the flood-gate being first placed at a proper angle for letting on the water. The invention here claimed is the before described horizontal water-wheel in the shaft and arms. The guard-ring or steps, and the mode of raising and lowering it, and the mode in which the floats are supported by the cranks and the gauge to let them down. The second or inclined race wheel. The shaft and arms of this wheel are the same as the horizontal water-wheel. The number of arms will be proportioned to the size of the wheel calculated for - one foot apart at their extremities. The arms, buckets, or floats, are attached by hinges to the ends of the arms. The buckets when down will be supported by these hinges against the front of the arms. Also the upper edge of the bucket will rest against the under side of the arm. The inclined race or pool composed of wood or other materials. It must be inclined to an angle of 6 or 8 degrees more or less, to be contracted at bottom to nearly the width of the bucket. The top of the race of course to be wider. The water from the race is conducted in a circular segment trough of about 3 feet in length and the course is adapted to the size of the wheel. On inclined plane is raised near the top of the circular trough on which inclined plane the buckets are raised and turned into the circular trough. Operation. The water descending down the inclined race acquire the necessary velocity and strike the swinging buckets at nearly right angles, thus producing the greatest effect. The invention here claimed is the before described inclined race or pool and circular segment trough and the construction of the swinging buckets to act at nearly right angles with the water. Also the inclined plane for raising and turning the swinging buckets into the circular trough.

For a further illustration of our invention, we refer to the models and drawings of the same deposited in the Patent Office.

The inventors whereof we have pleasure to subscribe

This is the frame for supporting the swinging basket whilst the frames of arms and buckets are lowered on the stone shaft. The guard ring & steps. A metallic ring encircling the shaft having projections or teeth on the lower side as suspended by ropes or chains from a windlass placed on the horizontal cog wheel to be hereafter described. This guard ring is for keeping the frame of arms and buckets at any required height on the shaft by means of the teeth on the ring catching in the notches of the hub which supports the arms. It also catches in grooves cut in the shaft to prevent it turning. A horizontal cog wheel which communicates motion to the mill is placed near the top of the shaft. Upon this wheel is put a windlass or capstan having two sets of chains on it passing over pulleys placed near the shaft and attached to the guard ring by which it is raised or lowered on the shaft. The sliding gauge. In the frame of the fore bay is fixed the sliding gauge. This gauge consists of an upright shaft or stock with a string behind it and working in a dovetailed groove. An arm projects from the upright stock on shaft at right angles and passing over the cranks & wheel keeps the swinging basket horizontal. when it is required to let down the basket the gauge is let down to touch the top of the crank handle which turns the circular head and let down the basket. The fore bay and trough. In front of this horizontal water wheel is a swinging gate or water divisor turning on two points fixed on the front of the fore bay. It is kept at any required angle by means of a strap or bar of iron having a slot or opening in it attached at one end to the gate and the other extending to the wall or frame of the fore bay where a screw passing through the slot fixes the gate at any angle and lets the water onto the wheel in any required angle. the wheel turns in a circular trough of a size adapted to the size of the wheel and the water is made to pass off in a proper outlet.

Operation - When it is required to lower the frame of float or boat to the water, the float is turned upside down, left in a horizontal position, and the frame is lowered on the water surface. The frame of the boat or float

is then turned by hand on the screw shaft and lowered to any required height. The guard ring is then let down by the windlass and the teeth in the ring catch into the notches of the ring or hub of the frame of arms and buckets. The swinging buckets are then let down by the gauge and the horizontal wheel set in motion the flood-gate being first placed at a proper angle for letting out the water.

The invention has claimed in the before described horizontal water wheel is the spiral screw shaft. The guard ring is stopped, not the mode of raising and lowering it, and the mode in which the floats are supported by the cranks and the gauge to let them down.

The second or second race wheel. The shaft and arms of this wheel are the same as the horizontal water wheel. The number of arms will be proportional to the size of the wheel calculated for — on — feet apart at their extremities — The swinging buckets or floats are attached to rings to the ends of the arms. The buckets when down will be supported by these rings against the front of the arm. Also the upper edge of the bucket will rest against the outer side of the arm.

The inclined race or spout is made of wood or other material. It must be inclined to an angle of 6 or 8 degrees more or less, to be contracted at bottom to nearly the width of the bucket. The top of the race opening to be wider. The water from the race is conducted in a circular segment trough of about 3 feet in length and the curve is adapted to the size of the wheel. On inclined race is raised from the left of the circular trough on which inclined plane the swinging buckets are raised and turned into the circular trough.

Operation. The water descending down the inclined race acquires the necessary velocity and strike the swinging buckets at nearly right angles, thus producing the greatest effect. The invention here claimed is the before described inclined race or spout and circular segment trough and the contraction of the swinging buckets to act at nearly right angles with the water. Also the inclined plane for raising and turning the swinging buckets into the circular trough.

For a further illustration of our invention, we refer to the models and drawings of the same deposited in the Patent Office.
